[57] CLAIM

The ornamental design for a tanning booth, as shown and described.

DESCRIPTION

FIG. 1 is a front perspective view of the tanning booth with the door closed showing my new design;

FIG. 2 is a rear perspective view of FIG. 1;

FIG. 3 is a top plan view of FIG. 1;

FIG. 4 is a front perspective view of the tanning booth with the door open.

The bottom of the tanning booth is understood to be flat and unornamented.

FIG 1

FIG 2

FIG. 3

FIG. 4
